MERLE J. WIGHTMAN, OF SEATTLE, WASHINGTON, ASSIGNOR TO RAILWAYS' ACCESSORIES COMPANY, OF SEATTLE, WASHINGTON, A CORPORATION

RAIL-JOINT.

1,183,260.

Specification of Letters Patent. Patented May 16, 1916.

Application filed November 25, 1913. Serial No. 802,952.

To all whom it may concern:

Be it known that I, MERLE J. WIGHTMAN, citizen of the United States, residing at Seattle, in the county of King and State of Washington, have invented a certain new and useful Improvement in Rail-Joints, of which the following is a specification.

My invention relates to improvements in devices which are generally referred to as rail joints and which are adapted to unite rigidly and firmly the rails forming a track-way of a railroad; and the object of my improvement is to provide a rail joint which may be so constructed that the abutting ends of two rails shall be united firmly so that there shall be no relative motion of said abutting ends and any wave action under the weight of a passing train will be the same through the rail junctures as it is through and along the body of the rails and when so united the top surface of the heads of such rails shall be maintained in practical alinement, as rigidly and firmly as it would be if they were welded together, and a further object of my invention is to provide a rail joint adapted to secure and maintain said alinement regardless of difference in the sizes of said rails due to inaccuracies in rolling, and a further object of my invention is to provide a rail joint, the parts of which are comparatively inexpensive to make and may be readily adjusted in position or removed and replaced by like new parts.

I attain these objects by devices illustrated in the accompanying drawings, in which—

Figure 1 is a view in perspective of one form of my invention, while Fig. 2 differs from Fig. 1 only in the simplification of certain of its parts. In said Figs. 1 and 2 I have shown certain features which I do not claim in this application, but which I shall incorporate and claim in another application for United States Letters Patent which I shall file subsequent to the date hereof.

In Figs. 3 and 4 are shown a variation of form, wherein is introduced a tie-plate supporting member, functioning to accomplish the same working result as the construction shown in Figs. 1 and 2; Fig. 3 being a view in side elevation with a portion of one of its parts broken away; Fig.

4 being a view in vertical-section on broken line $u-u$ of Fig. 3. Fig. 5 is a view in side elevation of a modified form of my invention, illustrating a form wherein a single bolt, centrally positioned, may be made to hold two rails in permanently rigid relation. Fig. 6 is a view in vertical cross-section on broken line $x-x$ of Fig. 7, and Fig. 7 illustrates the same by a view in side elevation wherein a portion of the base plate is broken away to more fully disclose other parts. In said Figs. 6 and 7 I have shown features which I do not claim in this application, but which I shall incorporate and claim in another application for United States Letters Patent which I shall file subsequent to the date hereof. Fig. 8 illustrates by a view in perspective, still another and preferred form of a rail joint embodying my invention; Fig. 9 is a view in perspective illustrating the abutting ends of two rails wherein broken lines and arrows indicate, diagrammatically, points of support and direction of strains when two rails are joined in accordance with my invention, and Fig. 10 is a view in perspective of a detail embodied in Figs. 6 and 7.

Like reference numerals indicate like parts throughout the drawings.

It has been found that the steel rails, of any given form, employed in the construction of track-ways of railroads, are not uniform in their cross-sectional dimensions. In some instances I have found a difference between two rails of the same lot and kind amounting nearly to one-sixteenth of an inch in the respective distances between the bottom of the bases and the top of the heads of such rails. Generally I have found, however, that most frequently the greater part of such differences exists in the relative vertical dimensions of the rails' webs, while the other parts of the rails, comprising the heads and the bases, in most cases are practically uniform with respect to vertical dimensions.

Heretofore the forms of devices employed for joining rails whose webs varied in height have been defective to a degree that adjacent rails could not be held permanently in fixed relation, since such devices have been so constructed and applied that any difference in the vertical dimensions of the webs

which were adjacent to each other was made manifest by an unequal pressure between the rail ends and the clamping members, which unequal pressure permitted relatively 5 lateral and vertical movements of contiguous parts to cause abrasion between such parts, with the final result of producing an unstable or rapidly disintegrating joint.

By the use of my invention all rails will 10 be held in practical alinement with respect to the top surface of the rail heads since any difference in the vertical dimensions of the respective heads of adjacent rails, generally, will be found to be negligible, and, further- 15 more, by my invention the parts applied between the bases and the heads of adjacent rails are sure to tightly fit and firmly se- 20 cure both such rails, against all relative movement whatsoever, except the necessary movements under expansion and contrac- 25 tion.

In Fig. 1, I have illustrated two abutting rail-ends 34, 34 on opposite sides of which are placed fish plates 35, 35, only one of 30 which is shown in the accompanying drawing. The fish plates 35, 35 are each pro- 35 vided, on its top edge, with an outwardly projecting flange 36, under which flange 36 supporting blocks 37, 37 are adapted to 40 abut at their upper ends. The supporting blocks 37, 37 are provided with notches on 45 their outside surfaces with which the ends of a semi-circular pressure equalizing mem- 50 ber 38 are adapted to engage, the lower edge 55 of said semi-circular member 38 being dis- posed to rest against an upwardly extended lug or member 39 that is provided on base plate 40. The rail joint illustrated in Fig. 60 1 is similarly constructed on both sides of the rail and by the action of its various parts the abutting rail-ends are held in sus- pended relation above said base plate and, under the pressure of a passing wheel load, the under surfaces of the rail heads are 65 forced into intimate contact with the upper edges of the fish plates, when the lowermost edges of the clamping members are pressed into close contact with the upper surfaces of the base flanges of the rails. By this 70 form of construction the use of bolts for lateral pressure is rendered unnecessary, though they may advantageously be retained to hold the rails against longitudinal creep- 75 ing or separation.

In Fig. 2 I have illustrated a form of rail joint in which are used fish plates 41, 41, only one of which is shown, that are similar to the fish plates 35, 35 of Fig. 1 and wherein, on either side, a clamping member 42 80 operates to accomplish the combined func- 85 tion of the parts 37, 37 and 38 illustrated in Fig. 1. The clamping member 42 is formed on its lower side with two legs or projections 43, only one of which is indicated, that

afford means whereby independent contact 65 against the upper surface of the base flange of each of the abutting rails is secured and the semi-circular shape of such member 42 assures a one point equalizing contact against a lug 44 that is provided on a base 70 plate 45 which is similar to the base plate 40 of Fig. 1.

It will readily be seen that the construction illustrated in Figs. 1 and 2, besides insuring a continuing lateral supporting pressure, 75 has the advantage of automatically equalizing the said pressure upon all of the clamping members, under varying vertical stresses due to moving loads.

In the device illustrated in Figs. 3 and 4 80 the combined functions of the fish plates 41, 41 and the clamping members 42, 42 of Fig. 2, are accomplished by suitably formed fish plates 46, 46, each of which is cut away on its lower edge intermediate its two ends, as 85 shown in Fig. 3, to secure positive inde- 90 pendent contact of each of said plates 46, 46 against the upper surface of the base flange of each of the rails 47, 47. The outer surfaces of the lower edges of the fish plates 46, 46 thus formed, bear throughout their full length directly against the inner sur- 95 faces of the flanges 48, 48 of a channel shaped base plate 49, which base plate 49 is adapted to rest upon a transverse ridge 50 100 that is formed in a rider plate 51 that may be secured to a tie, as illustrated in Fig. 3, the operation of this structure being such that when a downward thrust is exerted on the abutting ends of the rails 47, 47, the fish 105 plates 46, 46 will be forced inwardly and the head of each of the rails 47, 47, will be pressed downwardly onto the top edge of the fish plates 46, 46, thus maintaining the under surface of such rail heads in fixed 110 alinement and maintaining the rails 47, 47, in a suspended position above the base plate 49, as illustrated in Fig. 4, the equalization of load pressure on the various parts forming the joint being secured by resting the 115 plate 49 on the ridge 50.

In Fig. 5, which illustrates a theoretical rather than a practical embodiment of my invention, 52, 52 are the abutting ends of two rails and 53, 53 are fish plates, only one 115 of which is shown in the accompanying drawings, that are adapted to secure the ends of the rails 52, 52 in their proper position. The fish plates 53, 53 have their lower central portions cut away whereby bearing 120 surfaces 54, 54 are provided at the ends thereof, adapted to bear on the top surface of the base flange of each of the rails, the top edge 55 of each of the plates 53, 53 being curved convexly whereby the bearing 125 of the rail heads on the top edge of each of said fish plates shall be at a point near the ends of such rails only, the said fish plates

being secured to the rails by a single centrally positioned bolt 56 which extends through the web of the rails at their point of abutment.

5 In this Fig. 5, I have shown the upper supporting surface 55 of the fish plate 53 as a curve, rather than a straight line, to better illustrate the principle underlying my invention, which is that of a rail joining 10 means comprising four independent theoretical points of contact or pressure, as diagrammatically illustrated in Fig. 9. While in practice one of these theoretical points must bear as a line, rather than as a point, 15 so as to engage the head of each of two rails, at the junction thereof, nevertheless, the total weight exerted by or upon both of said rails, when considered as a single unit, is sustained, theoretically, upon a single point, as hereinafter more fully set forth. The radical departure of my invention from hitherto existing practice, it will therefore be seen, consists in the adapting of means for forcing both heads of two 20 joined rails toward a theoretical common point, in approach to which they become, both independently and coördinately, rigidly suspended or fixed, through the reciprocal action of all forces applied to, by, or 25 upon, the completed unit, either initially at installation, or in subsequent actual service.

In Figs. 6 and 7 a base plate 57 is disposed on a railroad tie, or ties as 58, and provided with holes through which railroad spikes 59, 35 59 may be driven to secure the base flanges 60, 60 of two rails, the heads 61, 61 of such rails being supported by fish plates 62, 62 disposed one on each side of the rail webs, each to extend between the tops of the base 40 flanges 60, 60 and the undersides of the heads 61, 61. I have shown bolts 63, 63 and nuts 64, 64 that may serve to aid in binding together the rails and the fish plates, but such bolts and nuts may, if desired, be dispensed 45 with, since the weight of the rails and the action of the spikes 59, 59, by their downward pressure, serve to transmit a supporting strain through each of the outwardly and downwardly extending flanges 65, 65 of the fish 50 plates 62, 62 to the inner oblique surfaces 66, 66 of the upwardly projecting flanges of the base plate 57. The flange 65 of each of the fish plates 62 constitutes an integral part of said fish plate 62, as shown more particularly 55 in Fig. 10, and extends along the central portion thereof between the vertical slots 67, 67 as shown in Fig. 7; thus each of the rail ends serves to act as the keystone of an arch, being retained in its position by the 60 wedging action of the surfaces 66 and 68.

Manifestly the pressure on the inner oblique surfaces 66, 66 of the upwardly projecting flanges of the base plate 57, being exerted at a point centrally located between

the two ends or points of contact of the 65 fish plates 62, 62 with the upper surfaces of the bases 60, 60 of the abutting rails, causes equal pressure on each of such surfaces irrespective of all differences in the dimensions of the webs of the two rails. To localize pressure at a central point of said fish plate 62, substantially in line with the junction of the rails, the flange 65 of said fish plate 62 is curved or equivalently angled on its outer edge from its middle toward its 70 opposite end whereby its bearing against the inner surface 66 of the flange of the base plate 57 is mechanically centered. The outer edge of the flange 65 is shown in an exaggerated curve, at 68, in Fig. 10. It will be 75 noted that the inner surface 66 of the flange of the base plate 57, is shown, in Fig. 6, as being straight, but it is obvious that said surface may be made correspondingly curved or angled to fit the outer surface 68 80 of the flange 65, or both of said surfaces may be otherwise shaped to produce substantially the same result, *i. e.* equal pressure between the fish plates and the rails at 85 each end of said fish plates. 90

Fig. 8 is a view in perspective of a preferred and more practical form of rail joint embodying the essential features of my invention, as hereinbefore described, but in which the fish plates 70, 70 of which only one 95 is shown, are slightly different from the fish plates 62, 62 of Fig. 6, and in which four bolts 69, 69, 69, 69 are provided to bind together the said fish plates and the rails 71, 71, which bolts are not, however, essential 100 for the proper functioning of this form of my invention. A bolt 72, extending downwardly through the flange 73 of each of the fish plates and through the base plate, serves the same purpose as the spikes 59, 59 of 105 Figs. 6 and 7.

Fig. 9 illustrates diagrammatically the four points, (surfaces) of contact and the direction of strains in my rail joint, shown in the structures of Figs. 6, 7 and 8. In 110 said Fig. 9, 74, 74' are the points (surfaces) of pressure under the heads 75, 75' of the two rails, 80 being the point (surface) of outward pressure exerted laterally on the oblique surface 66 of the base plate 57, by 115 the curved or angled surface 68 of the flange 65 of the fish plate 62, as illustrated in Fig. 6, but not shown in Fig. 9. From this point (surface) 80, the said pressure is resolved into equalized and localized downward pressures upon the points (surfaces) 77 and 79, on the base flanges of both rails. Thus, if the load is approaching in the direction of the arrow, the pressure is at point (surface) 74, outward to point (surface) 80 and thence, 120 simultaneously, to points (surfaces) 77 and 79 on the bases of both rails. Likewise, if the load is approaching from the opposite 125

direction, the pressure is at point (surface) 74', outward to point (surface) 80 and thence, simultaneously, to points (surfaces) 79 and 77. It is therefore apparent that 5 the resultant pressures, whether originating from a load on one rail or the other, are disposed identically the same. Hence, it will be seen, each of the rail ends functions as the keystone of a separate arch, each arch 10 being primarily unstable, but made stable by coördination with the other arch. Moreover, when thus distributed, the necessarily intermittent and varying pressures, due to 15 passage of car wheels, in no wise affect the continuing stability and tightness of this joint, since the wedging or clamping angle chosen for its impinging surfaces is such that the frictional engagement of the fish plates with the upturned flanges of the base 20 plate, is so positive as to hold, by frictional grip against vertical recovery and make them practically integral. It will thus be clear that in a rail junction embodying my 25 invention as described, any pressure in either arch, as above explained, due to weight that might rest wholly on one rail, at or near the abutting ends of the two rails, would be simultaneously transferred to and substantially duplicated in the other at a predetermined 30 ratio and hence any depression due to weight would affect the end of one rail as much as it would the other rail, to preserve a constant relation with respect to any 35 movement or vibration of the ends thereof, and the structure must, therefore, continue indefinitely to function identically as at the beginning. In further elucidation of said Fig. 9, the four points of pressure therein 40 diagrammatically shown may be considered as disposed in the approximate relative positions of the points of a geometrical tetrahedron, wherein the points 74, 74', considered as a unit, *i. e.*, as a common center, comprise the upper point thereof and the points 45 77 and 79 are the two base points on a given face. The point 80, therefore, is disposed at the remaining or opposite point of the base of said tetrahedron and, referring to Fig. 5, is represented by the bolt 56 of that theoretical 50 structure. In Fig. 8, however, wherein I show my preferred form of the invention, the said bolt 56 of Fig. 5, is replaced in function by the flange 73 impinging against the inclined inner surface of the flange of the 55 base plate.

It will be manifest upon consideration of the structures of Figs. 1, 2, 3, 4, 6, 7, 8 and 9, embodying my invention, as hereinbefore described, that weight, either constant or varying, when disposed at or near the junction of the abutting rails, will force all parts, by self adjustment, into more intimate contact, *i. e.*, cause them to concentrate, regardless of variations resulting from wear, or any dif-

ferences in dimensions resulting from imperfections in the rolling process, in the same manner that weight upon the keystone of an arch exerts its form with a tendency to press all its members closer together; this result being in marked distinction from 70 hitherto existing practice wherein the component parts of all rail joining structures have tended, under service, to disintegrate or scatter.

Furthermore, the fastening of rails at 75 their juncture, by means of an arch support, has hitherto been unsuccessful for the reason that any looseness that existed or developed in the support of one of the said rails, tended constantly to increase, resulting 80 finally in a rigid support of but one of the rails, the other developing an ever increasing looseness.

It will be understood that the principle 85 of my construction could be readily adapted to the alinement of the upper surfaces of rail heads, rather than the under surfaces thereof, as contemplated throughout this specification. To accomplish this result it would be only necessary to form the upper 90 surfaces of the fish plates or supporting members of such relative heights, for each of the rails, as would be required to compensate for any differences that might exist in the sizes of the heads thereof. 95

Obviously, the form and dimensions of the different parts of a structure embodying my invention may be modified to suit different conditions of service without departing from the spirit thereof. 100

It will be further understood that with rails rolled to a high degree of uniformity of size, the principle of my invention would not be departed from if parts herein shown and described be reversed or turned upside 105 down with respect to the points of contact against heads and flanges of the rails.

I claim:

1. In a rail joint of the class described, the combination of two abutting rail end portions, each supported in a separate arch, and means for equalizing the pressures in the said two arches. 110

2. In a rail joint of the class described, the combination with two abutting rail end portions, of fish plates engaging said rail ends, a supporting base plate, means associated with said fish plates and said base plate whereby said fish plates are caused to be pressed laterally toward said rail ends under 115 the weight of a passing wheel load and means for automatically equalizing such pressure against both of the said rail ends. 120

3. In a rail joint of the class described, the combination with the abutting end portions of two rails, of fish plates disposed one on each side thereof to engage with the under surface of the head of each of said 125

rails, each of said fish plates having its lower edge cut away for a portion of its length between its two ends whereby such ends may rest one on the top surface of the 5 base flange of each of said rails, and means for exerting an inwardly directed pressure upon each of said fish plates, said means being so disposed as to automatically equalize the said pressure against both ends of both 10 of said fish plates.

4. In a rail joint of the class described, the combination with the abutting end portions of two rails, of fish plates disposed one on each side thereof to engage with the 15 under surface of the head of each of said rails, each of said fish plates having its lower edge cut away for a portion of its length between its two ends whereby such ends may rest one on the top surface of the 20 base flange of each of said rails, and means engaging with said fish plates whereby an inwardly directed pressure is exerted upon and automatically equalized against both ends of each of said fish plates regardless of 25 the amount or relative position of the wheel load upon either of said rails.

5. In a rail joint of the class described, the combination with the abutting end portions of two rails, of fish plates disposed one 30 on each side thereof to engage with the under surface of the head of each of said rails, each of said fish plates having its lower edge cut away for a portion of its length between its two ends whereby such ends may 35 rest one on the top surface of the base flange of each of said rails, a base plate, and means disposed to support said rail ends and said fish plates in an arch-like structure.

6. In a rail joint of the class described, 40 the combination with the abutting end portions of two rails, of fish plates disposed one on each side thereof to engage with the under surface of the head and the top surface of the base flange of each of said rails, 45 and means for exerting an inwardly directed pressure upon each of said fish plates, said means being so disposed as to automatically equalize the pressure of each of said fish plates against both of the rails.

50 7. In a rail joint of the class described, the combination with the abutting end portions of two rails, of fish plates disposed one on each side thereof to engage with the under surface of the head and the top surface of the base flange of each of said rails, means 55 for exerting an inwardly directed pressure upon each of said fish plates, and means for automatically equalizing the pressure of each of said fish plates against the under 60 surfaces of the heads of both of the rails.

8. In a rail joint of the class described, the combination with the abutting end portions of two rails, of fish plates disposed one on each side thereof to engage with the under

surface of the head and the top surface of the 65 base flange of each of said rails, a base plate having upwardly projecting flanges disposed on either side of said rail ends, and means engaging with said flanges, whereby each of said fish plates shall be caused to 70 exert an equal lateral pressure against both of the rails.

9. In a rail joint of the class described, the combination of two abutting rail end portions, supporting members engaging said 75 rail ends, a base plate, and means for resolving any pressure exerted upon either of said rail ends into equal pressures between said supporting members and both of said rails.

80 10. In a rail joint of the class described, the combination of two abutting rail end portions, fish plates engaging said rail ends, each of said fish plates having its lower edge cut away for a portion of its length between 85 its two ends, a base plate, and means for directing a mechanically centered inward pressure upon said fish plates.

11. In a rail joint of the class described, in combination, the abutting end portions 90 of two rails, supporting means, and compression means so disposed that a wheel load on either of said rail ends shall be resolved into an inward pressure exerted by the said supporting means equally against 95 both rails.

12. In a rail joint of the class described, in combination, the abutting end portions of two rails, clamping members supporting one of said rails in an arch and means for 100 equalizing the pressure of said clamping members against both of said rails.

13. In a rail joint, the combination of two abutting rail end portions, each supported in a separate arch and means for maintaining pressures in the said two arches in a predetermined ratio.

14. In a rail joint of the class described, the combination of two abutting rail end portions, supporting members engaging said 110 rail ends; a base plate; and means for resolving any pressure exerted upon either of said rail ends into pressures between said supporting members and both of said rail ends in a predetermined ratio.

115 15. In a rail joint of the class described, in combination, the abutting end portions of two rails, supporting means, and compression means, so disposed that a wheel load on either of said rail ends shall be resolved into 120 an inward pressure exerted by the said supporting means in a predetermined ratio against both rails.

125 16. In a rail joint of the class described, the combination with two abutting rail end portions, of a base plate; and supporting members adapted to engage said rail end portions and said base plate to support said

6 rail portions in arched relationship above my name this 15th day of November, A. D.
said base plate, said supporting members 1913.
and said base plate having such angular
wedging relation as to hold automatically,
5 by frictional grip, against any relative
movement therebetween.

In witness whereof, I hereunto subscribe

MERLE J. WIGHTMAN.
